UNITED STATES PATENT OFFICE.

BENJAMIN EDWARD MEACHAM, OF LORAIN, OHIO, ASSIGNOR TO AMERICAN STOVE COMPANY, OF ST. LOUIS, MISSOURI, A CORPORATION OF NEW JERSEY.

GAS RANGE.

Application filed February 2, 1928. Serial No. 251,338.

This invention relates to improvements in gas ranges and more particularly to a gas range having a closed front under the cooking top behind which is concealed the gas manifold and gas cocks for supplying gas to the cooking top burners.

The primary object of the invention is the provision of a gas stove of the type described which is of an improved appearance in that it presents a smooth and neat front.

Another object of the invention is the provision of a gas stove of the character described having at its front below the cooking top operating handles conveniently placed for the operation of the gas cocks for the burners.

Another and further object of the invention is the provision of a gas stove of the character described wherein the air and gas intake ends for the cooking top burners project through the end of the burner box and operating handles for the gas cocks are carried to a point at the front of the range below the cooking top so as to be conveniently placed for the hand of the operator of the stove.

A still further object of the invention is the provision of a stove of the character described which is of a construction whereby it is applicable to standard and approved stove parts such as top burners, top grates, gas cocks, and manifold supply pipes.

Another and further object of the invention is the provision of a construction wherein the products of combustion from the top burners can not enter the mixing tubes and thus disturb the admission of primary air for the combustion and thereby impair the operation and combustion of the burners.

A still further object of the invention is the provision of a construction wherein gas cocks are located in such a position that adjustment or removal of them can be easily made by the easy and ready removal of the end shelf of the cooking top.

A still further object of the invention is the provision of a construction wherein the gas cock is so positioned as to not become overheated which tends to destroy the lubricant in the valves and make them hard to operate.

A still further object of the invention is the provision of a gas stove of the character described which is cheap and simple of manufacture, highly pleasing in appearance and efficient in operation.

Referring now to the drawings:

Figure 1 is a view in front elevation of a complete gas range built in accordance with my invention.

Figure 2 is a horizontal sectional view 60 showing the arrangement of the burners, gas cocks and gas cock operating handles.

Figure 3 is a detailed view, partially in vertical section, of one of the burners and the construction of the operating handle for the 65 gas cock thereof.

Figure 4 is a view in front elevation of a complete gas range illustrating the modified form of my invention.

Figure 5 is an end view of the stove appearing in Figure 4.

Figure 6 is a top plan view of the cooking top of the stove appearing in Figure 4.

Figure 7 is an enlarged detailed view, partially in vertical section, showing the handle 75 for operating one of the gas cocks for one of the burners of the modified form of the invention.

Referring now to the drawings, particularly Figures 1 to 3 inclusive, the entire gas range is designated by A and with the exception of the concealed manifold and gas cocks for the cooking top is more or less of conventional form in that there are the usual legs 10 supporting a stove base 11 upon one end of which is mounted the oven 12 and broiling oven 13. The stove shown in the drawings is what is known as a right-hand oven stove.

Gas is supplied to the two ovens by a gas 90 conduit 14 and a thermostatic control for the oven burners is provided at 15.

The cooking top of the range is at the left side or end of the frame, being designated by the numeral 16 and this cooking top can be provided with a solid or grate top as the desire may be. A common form of gas range construction is present in that there is a splasher back or plate 17 behind the cooking top and at the upper end of the splasher there is provided a shelf 18.

The space beneath the cooking top is closed in entirely by the stove back 19, end 20 and front 21. The front 21 is provided with an elongation 22 which extends beyond the end 20 of the range a distance equal to the width of the cooking top shelf 23 which shelf is removable as is a common construction in respect to gas ranges.

By reference to Figure 2 of the drawings 110

it will be seen that there are four burners in the four corners of the cooking top. The burners 24 and 25 are front burners and 26 and 27 the rear burners. These burners are provided with gas inlet manifolds 28 carrying at their ends mixing bells 29 which extend through the end wall 20 of the range rather than through the front wall of the range as is a common practice. The burners are supported in place by suitable longitudinal bars 30 which extend lengthwise of the range in the burner box beneath the cooking top.

The gas supply conduit for the cooking top burners is designated at 31 and makes in at the rear of the stove and extends along the end 20 thereof beneath the cooking top shelf 23 and is supported in spaced parallel relation to the end 20 of the range. The burner cocks or valves 32 have one end threaded into the conduit 31 while their other ends are provided with jets 33 which deliver gas into the mixing bells 29 of the stove burner manifolds.

By reference to the drawings it will be seen that from the front of the stove the gas conduit 31, the gas cocks 32, and the extending ends of the bells 29 are hidden from sight by the extending end portion 22 of the stove front.

It is essential that a convenient means of operation of the gas cocks be provided and this is present at the front of the stove in the form of four handles 34, one being for the control of each of the burners. These handles 34 are rotatable and each of them is provided with an elongated shaft or stem 35 extending into the burner box beneath the cooking top where they have connection with the short cranks 36 which are fastened to rotate with the stems. Each of the gas cocks 34 is provided with an arm 37 and pivotal bars 38 pivotally attached to the arms 37 as at 39 and pivotally mounted at 40 in the crank arms 36 complete an operative connection between the valves 32 and the valve operating handles 34 at the front of the range.

With the construction just described it will be seen that by oscillating the handles 34 the stove valves can be opened or closed as desired.

No particular description of the valves 32 has been given as it is thought it will be readily apparent that they are of a common form of rotary plug valve construction.

The solid front 21 below the cooking top is provided in its bottom with a sliding drawer 41 wherein utensils may be stored or kept while intermediate the drawer and the cock operating handles 34 is a sliding dirt catching tray 42 which may be periodically removed for cleaning and guards the drawer 41 from dirt which might fall through the cooking top or from the burners.

Referring now to the modified form of the invention appearing in Figures 4 to 7 of the drawings it will be seen that the stove proper

is designated by B and is of that type known as a left hand oven construction.

In these figures of the drawing the cooking top, splasher back, splasher back shelf, stove legs, base, cooking and broiling ovens, gas delivery pipe to the ovens, thermostat, utensil drawer and sliding dirt tray are given the same numerals as has been given to them in those figures of the drawings wherein the preferred form of the invention is illustrated.

In this form of the invention the cooking top shown is of the open type being provided with grids 43 beneath which are positioned the two front burners 44 and the two rear burners 45 having gas manifolds 46 terminating in the mixing bells 47 which extend slightly beyond the range end 48.

As was the case in respect to the preferred form of the invention the range front 49 beneath the cooking top, is of a solid construction and has an extending end portion 50 beyond the end 48 of the range and that the removable shelf 51 of the cooking top is positioned above this extending portion of the range front.

The space beneath the cooking top is closed in completely by the range front 49, end 48 and the rear wall 52 of the range.

The gas delivery pipe 53 for the cooking top burners parallels the back of the range and extends along the end 48 of the range in spaced parallel relation thereto. A plurality of gas cocks 54, one for each burner, are provided for delivering gas from the conduit 53 into the mixing bells 47 of the stove burners. These gas cocks are of a common rotary plug type and by reference to Figure 7 of the drawings it will be seen that they have extending arms 55 to which the rods 56 are pivotally connected as at 57. These rods extend downwardly and forwardly to a point just in back of the extension portion 50 of the range front 49. Arranged in a vertical row down the extension portion 50 of the stove front are four handles 58 attached by screws 59 to stub shafts 60 which are mounted for oscillation in the bosses 61 provided on the inner face of the extension portion 50. Each of the stub shafts is provided with a pin 62 which prevents them from being pulled outwardly through their supporting openings.

The lower ends of the rods 56 are provided with forks 63 pivotally attached to the rod as at 64 and these forks are in turn provided with pins 65 extending through the slotted ball shaped ends 66 of the stub shafts 60 whereby a universal joint is provided between the lower ends of the rods 56 and the stub shafts 60 of the operating handles 58.

At the front of the range adjacent the cock or valve operating handles 58 is a button 67 which operates a lighter for the burners of the cooking top. The lighter valve operated by

the button 67 is of a standard construction in that it is spring seated and a pull on the button 67 opens the valve and allows gas to flow to the pilot light for the purpose of causing a larger flame in the pilot for lighting the main cooking top burner. 70

From the foregoing it will be seen that in both forms of the invention a range is provided which is of a pleasing and neat appearance in that the front of the stove presents only very small handles for operating the burner valves or cocks while when looking down upon the top of the stove the gas cocks, gas supply pipe and the ends of the burner mixing tubes are hidden from view by the removable cooking top shelf. 75

The construction is such that it is very easy to keep the stove clean and the operation of the stove is excellent by reason of the fact that 20 the bells at the ends of the burner mixing tubes receive their air exteriorly of the burner chamber which makes for a much better combustion at the burners. 80

It will be understood that should this stove 25 be provided with a closed cooking top it would be necessary to provide air inlet holes or openings in the end 20 of the burner box. 90

Having thus described my invention what I claim and desire to secure by Letters Patent is:

1. A gas range having a cooking top, a burner box beneath said top and closed in at its four sides, front and rear burners in said burner box, said burners having mixing tubes 35 and mixing bells, said mixing bells extending through openings provided in the end wall of said burner box, a gas delivery pipe and cut-off valve for said burners at the end of said burner box beyond said bells, controlling handles for said valves rotatably mounted upon the front wall of said burner box and provided with elongated shafts extending into said burner box, and operative connection between said shafts and said cut-off valves, for the 40 purpose described. 100

2. A gas range having a cooking top, a burner box beneath said cooking top and closed in at its four sides, front and rear burners in said burner box, gas supply and 50 cut-off valves for said burners at the end of the range and said burner box, and controlling handles for said valves rotatably mounted in a horizontal line across the front of said burner box beneath said cooking top. 105

3. A gas range having a cooking top, a burner box beneath said cooking top and closed in at its four sides, front and rear burners in said burner box having mixing tubes extending through the end wall of said burner 55 box, a gas supply pipe and cut-off valves for said burners at the end of the range beyond the extending ends of said burner mixing tubes, controlling handles for said cut-off valves mounted in a vertical line upon the 60 front wall of said burner box, operating rods 110

interconnecting said controlling handles and said cut-off valves, said operating rods extending downwardly and forwardly from said cut-off valves and having universal connection with said controlling handles, for the purpose described. 70

4. In a gas range having a cooking top and a burner box therebeneath having therein a plurality of burners, a gas supply pipe extending across the end of the range exteriorly of the burner box and having connection for gas delivery to said burners, valves for controlling the delivery of gas to the burners, controlling handles for said valves rotatably mounted on a horizontal line across the front of said burner box beneath said cooking top, said handles provided with elongated stems extending into the burner box, and said rods carrying crank arms, having connection with said valves for operating the valves when the controlling handles are rotated. 80

5. A gas range having a cooking top with a burner box therebeneath, burners in said burner box, said burners having elongated mixing tubes extending lengthwise of said burner box and terminating at the end wall of the burner box in mixing bells which extend through the burner box end wall, a gas supply pipe extending across the end of the range exteriorly thereof and across the ends of the mixing bells, a gas supply connection between each mixing bell and the gas supply pipe, a controlling valve in each of said gas connections, an operating bar for each of said gas valves extending through the end wall of the burner box and into the same, operating handles for said gas valves rotatably mounted in a horizontal line across the front of said burner box beneath the cooking top and provided with elongated stems extending into said burner box at right angles to said bars, and said stems provided with crank arms having connection with said bars for operating the bars and the valves when the controlling handles are rotated. 95

6. A gas range having a cooking top and a removable shelf at one end thereof forming an extension beyond the range, a burner box beneath said cooking top having therein front and rear burners, the front wall of said cooking top having an extension beyond the end thereof beneath said removable shelf and of a depth substantially the same as the depth of the range front beneath the cooking top, said burners having elongated horizontally extending mixing tubes terminating in mixing bells which protrude through suitable openings in the end wall of the burner box beneath said shelf, a gas supply pipe extending across the end of the range exteriorly of the burner box and beneath said shelf, controlling valves for said burners positioned between the gas supply pipe and the mixing bells, controlling handles for said valves rotatably mounted upon the front wall of said burner box and 120

having operative connection with the valves, and said gas supply pipe, cut-off valves and valve operating mechanism hidden from sight by the front wall of the range and its extension and the removable shelf, whereby said parts are hidden from view to present a stove of neat appearance.

7. In a gas range having a cooking top with a burner box therebeneath, front and rear burners in said burner box having their mixing tubes extending lengthwise of the burner box and terminating in mixing bells extending through suitable openings in the end wall of the burner box, a gas supply pipe extending across the end of the range exteriorly thereof

and beyond said mixing bells, valves associated with said gas supply pipe for controlling the delivery of gas to the burners, said valves having elongated arms extending into the burner box lengthwise thereof, controlling handles for the valves rotatably mounted in a horizontal line across the front of said burner box beneath said cooking top, and said controlling handles provided with elongated stems extending into the burner box at right angles to said bars and having operative connection therewith. ²⁰

In testimony whereof I hereunto affix my signature.

BENJAMIN EDWARD MEACHAM.
